ALBERT EDWARD STEINKAMP, OF CINCINNATI, OHIO

HAIR CUTTING GAUGE

Application filed June 20, 1931. Serial No. 545,807.

The object of my device is to provide a gauge that will enable any ordinary person to cut or trim a man's or boy's hair with great speed and absolute accuracy.

5 I attain this object in the construction shown in the accompanying drawings. Similar figures refer to similar parts throughout both views.

Fig. 1 is a face view of a metal blank 10 stamped out and ready to be formed or shaped into the gauge shown in Fig. 2. It may be made of any metal but is preferably made of sheet brass $\frac{1}{8}$ of an inch thick.

Fig. 2 is a perspective view of the gauge, 15 complete and ready for use. The top or horizontal face of the gauge (as shown in Fig. 2) we shall hereinafter refer to as the "face side" of the gauge.

20 3 indicates the handle with which to hold the gauge.

4 is a flange along one-half of one side of the gauge; bent at right angle to the face-side of the gauge. The dotted line in Fig. 1 shows where the plate is bent to form the 25 flange.

5 is a "rest-end" designed to support the scissors when cutting hair.

6 indicates a number of prongs. These 30 prongs are bent at a point to leave short, horizontal extensions to the face-side of the gauge, while the remainder and longer ends of the prongs run parallel to and in the same direction as the flange.

The open spaces between the said short 35 horizontal extensions form the cutting line. To cut the hair the operator places the gauge on the head, resting it on the prongs and flange, with the face-side of the gauge in full view. By slowly moving the gauge forward, the prongs will push the hair up on end, and as the upright hair pass the prongs 40 they will move into the cutting line; there to be cut off with a pair of scissors, by placing the scissors on the gauge with one blade 45 on each side of the cutting-line.

The object of the flange is to prevent the 50 newly cut hair from passing this point too rapidly, thereby counteracting the pressure of the hair pushed up in front of the prongs. By this means the hair within the cutting-

line will be held upright, without bending, so that all the hair will be cut a uniform length. This insures an accurate and smooth job of hair cutting.

After the hair is all cut its accuracy may 55 be easily tested: By moving the gauge slowly over the surface of the head every defect will be readily noticed as the hair passes through the cutting-line.

Having explained my invention, what I 60 claim and desire to secure by Letters-Patent is:

A hair cutting gauge, made of an oblong plate of sheet metal, having a right-angle flange at one end on one side of the plate— 65 the other side, opposite the flange, having a number of prongs, each of said prongs (except the first one) being bent at a point to leave short, horizontal extensions to the face-side of the gauge, while the longer ends 70 of the prongs run parallel to and in the same direction as the flange.
